(57) **CLAIM**

The ornamental design for a brush head, as shown and described.

DESCRIPTION

FIG. 1 is a top right perspective view of a brush head showing the claimed design;

FIG. 2 is a front view thereof;

FIG. 3 is rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view, shown in an environment of use.

The evenly-spaced broken lines shown in FIG. 7 illustrate portions of the article, and form no part of the claimed design. The evenly-spaced broken lines illustrating a handle and bristles shown FIG. 8 illustrate environmental subject matter, and form no part of the claimed design.

1 Claim, 7 Drawing Sheets
